UNITED STATES PATENT OFFICE.

GEORGE HENRY WHEARY, OF RACINE, WISCONSIN.

TRUNK IRONING-BOARD.

1,387,028.

Specification of Letters Patent.

Patented Aug. 9, 1921.

Application filed July 9, 1920. Serial No. 395,113.

To all whom it may concern:

Be it known that I, GEORGE HENRY WHEARY, a citizen of the United States, and resident of Racine, in the county of Racine and State of Wisconsin, have invented new and useful Improvements in Trunk Ironing-Boards, of which the following is a description, reference being had to the accompanying drawings, which are a part of this specification.

This invention relates to improvements in trunk ironing boards.

An electric or other flat iron is now considered a necessary and a very desirable adjunct to a wardrobe trunk, and irons now almost universally form part of the outfit of the traveling public to permit the easy and expeditious pressing and ironing of wearing apparel soiled or wrinkled during traveling.

Heretofore, the ironing was done on any convenient table or stand which was not as firm as desired nor of a shape to permit the ironing of some garments in the most efficient manner.

It is one of the objects of the present invention to overcome the before mentioned objectionable features and provide an ironing board which is carried in the trunk and may be easily mounted in a firm position for use on the trunk when the trunk is in open position.

A further object of the invention is to provide a trunk ironing board in the form of an attachment which may be easily mounted in any ordinary wardrobe trunk.

A further object of the invention is to provide a trunk ironing board which is attachable to a wardrobe trunk section and when not in use may be easily swung to a folded position to permit the closing of the trunk sections.

A further object of the invention is to provide a trunk ironing board which is supported both in open or folded position entirely on the trunk.

A further object of the invention is to provide a trunk ironing board so arranged that garments to be ironed may be easily slipped over the end of the board.

A further object of the invention is to provide a trunk ironing board which is of simple construction, is strong and durable and is well adapted for the purpose described.

With the above and other objects in view, the invention consists of the trunk ironing board and its parts and combinations as set

forth in the claims and all equivalents thereof.

In the accompanying drawing in which the same reference characters indicate the same parts in all of the views:

Figure 1 is a front view of a portion of a wardrobe trunk provided with the improved ironing board;

Fig. 2 is a view taken at right angles to Fig. 1, showing the ironing board in extended supported position;

Fig. 3 is a rear detail view, on a larger scale, of a portion of the ironing board showing the supporting standard in folded position;

Fig. 4 is a detail sectional view of one end portion of the pivotal connection of the ironing board and a portion of the trunk;

Fig. 5 is a detail sectional view of the joint of the supporting rod; and

Fig. 6 is a detail sectional view of a portion of a modified form of attachment for the board.

Referring to the drawing, the numeral 8 indicates a drawer section, and 9 a wardrobe section of a wardrobe trunk which is provided with the usual garment hangers 10, pressure bar 11 and a shoe box 12. The improved ironing board comprises the board 85 member 13, the attaching means 14 and the supporting leg 15. The board 13 is of less width at its outer end portion to permit it to enter smaller portions of garments to be ironed, and the inner end of the board is 90 provided with two loops 16 which extend around and are rigidly fastened to a transverse supporting rod 17 forming part of the attaching means 14 before mentioned. Said rod at its opposite ends is journaled in opposite brackets 18 which are mounted on the opposite inner faces of the trunk section sides and offset inwardly toward each other from the side portions of the trunk. The rod 17 is of less length than the distance 100 between the trunk sides and on one end is shouldered as indicated by the numeral 17' to limit the endwise movement in that direction. The opposite end portion of the rod is provided with a slidable sleeve 19 105 which is yieldingly urged outwardly by a coiled spring 20 surrounding the rod and interposed between the sleeve 19 and a collar 21 mounted fast on the rod. The sleeve is formed with an elongated slot 22 to receive 110 the outer end portion of a pin 23 which limits the outer movement of said sleeve.

This construction permits the easy removal of the rod and the board by pressing the rod to the right against the tension of the spring 20 until the opposite end of the rod clears 5 its offset bracket and then swinging said cleared end upwardly or outwardly, the other end may then be disengaged from its supporting offset bracket. The rod is replaced by reversing the movements.

10 The board 13 toward its outer end portion has mounted on its under side a downwardly looped bracket 24 to the looped portion of which is hingedly connected the upper end of the two part supporting leg 15 before 15 mentioned. The lower end portion of this leg, when the ironing board is in open position, enters the socket member 25 mounted on the shoe box 12 and supports the outer end portion of said board. As said supporting leg extends downwardly and inwardly, a very rigid brace is formed to withstand the work. The two portions of the legs overlap each other and have flat adjacent faces 26 and are foldably connected together by a 25 headed pin 27 rigidly connected to one of the overlapped portions and extending loosely through the other overlapped portion to permit said portion to freely slide and swing to folded position. The headed pin 27 is sufficiently long to permit the lower portion of the leg to be moved laterally to clear the shoulders 26' formed by the flat faces 26, and the said lower leg part may then be folded in position shown in Fig. 3. 30 When folded, the parts are swung against the lower surface of the board and engage transverse holding and reinforcing members 28 and 28' mounted thereon. The holding member 28' is in the form of a pivoted latch 35 which may be turned to lock the parts in folded position. When the leg is in supporting position, a slidable sleeve 29 positioned on the upper leg part, is adapted to be slid over the overlapped parts and hold said 40 parts in alined position. The sleeve is provided with an elongated slot 30 to accommodate the pin 27, and said pin also serves as a stop to properly position the sleeve over the joint. 45 When the board is folded downwardly its lower end is adapted to extend to the rear of the socket member 25, which holds the board in said position. In the modified form shown in Fig. 6, the ironing board 13 is 50 provided with open loops or hooks 16' which removably connect the board to the transverse rod.

From the foregoing description, it will be seen that the trunk ironing board is of very 55 simple construction, and is well adapted for the purpose described.

What I claim as my invention is:

1. The combination with a trunk section having a shoe box, of an ironing board there- 60 for, comprising brackets mounted on the op-

posite side portions of the trunk section, a board member having a transverse rod at its inner end portion which removably engages the brackets, a socket member mounted on the shoe box, and a supporting leg member connected to the other end portion of the board and removably engaging the socket member of the shoe box. 70

2. The combination with a trunk section provided with a shoe box in its lower portion, 75 of an ironing board for the trunk section, comprising brackets mounted on the opposite side portions of the trunk section, a board member having a transverse rod at its inner end portion provided with a yielding 80 sleeve, said rod and sleeve removably engaging the brackets to hingedly connect the board to the trunk section, and a supporting leg member connected to the other end portion of the board member and removably engaging a part of the shoe box. 85

3. The combination with a trunk section provided with a shoe box in its lower portion, 90 of an ironing board for the trunk section, comprising brackets mounted on the opposite side portions of the trunk section, a board member having a transverse rod at its inner end portion provided with a yielding 95 sleeve, said rod and sleeve removably engaging the brackets to hingedly connect the board to the trunk section, a socket member mounted on the shoe box, and a supporting leg member hingedly connected to the other end portion of the board member and removably entering the socket member to hold said 100 board member in its upper position.

4. The combination with a trunk section provided with a shoe box in its lower portion, 105 of an ironing board for the trunk section, comprising brackets mounted on the opposite side portions of the trunk section, a board member having a transverse rod at its inner end portion provided with yielding sleeve, 110 said rod and sleeve removably engaging the brackets to hingedly connect the board to the trunk section, a socket member mounted on the shoe box, and a two-part-hinged-together supporting leg member hingedly connected to the other end portion of the board member and removably entering the socket member 115 to hold said board member in its upper position.

5. The combination with a trunk section provided with a shoe box in its lower portion, 120 of an ironing board for the trunk section, comprising inwardly offset brackets mounted on the opposite sides of the trunk section and having openings therein, a board member having a transverse rod at its inner end portion, the opposite ends of said rod removably 125 entering the bracket openings to form a hinge connection therewith, a yielding sleeve slidably mounted on the rod and engaging one of the brackets to maintain the rod in central position and permit the removal of 130

the rod from the brackets, a socket member mounted on the shoe box, a two-part-hinged-together supporting leg hinged at its upper end to the outer portion of the board and 5 foldable against said board, the lower end portion of said leg removably entering the socket member, and a sleeve slidably mounted on the leg and movable to a position to lock the two portions of the leg member in 10 alined position.

6. The combination with a trunk section provided with a shoe box in its lower portion, of an ironing board for the trunk section, comprising inwardly offset brackets mounted 15 on the opposite sides of the trunk section and having openings therein, a board member having a transverse rod at its inner end portion, the opposite ends of said rod removably entering the bracket openings to form a 20 hinge connection therewith, a yielding sleeve slidably mounted on the rod and engaging one of the brackets to maintain the rod in central position and permit the removal of the rod from the brackets, a socket member mounted on the shoe box, a two-part-hinged-together supporting leg hinged at its upper 25 end to the outer portion of the board and foldable against said board, the hinged portions of said leg overlapping each other and having adjacent flat faces and movable laterally and swingingly to folded position, a sleeve movable to inclose the overlapped leg portions and lock said parts in alined position, the lower end portion of said leg removably entering the socket member, and a sleeve slidably mounted 30 on the board for holding the supporting leg in folded position, the lower end portion of said leg removably entering the socket member, and a sleeve slidably mount-

ed on the leg and movable to a position to lock the two portions of the leg member in alined position.

35

7. The combination with a trunk section provided with a shoe box in its lower portion, of an ironing board for the trunk section, comprising inwardly offset brackets mounted on the opposite sides of the trunk section 40 and having openings therein, a board member having a transverse rod at its inner end portion, the opposite ends of said rod removably entering the bracket openings to form a hinge connection therewith, a yielding sleeve 45 slidably mounted on the rod and engaging one of the brackets to maintain the rod in central position and permit the removal of the rod from the brackets, a socket member mounted on the shoe box, a two-part-hinged-together supporting leg hinged at its upper 50 end to the outer portion of the board and foldable against said board, the hinged portions of said leg overlapping each other and having adjacent flat faces and movable laterally and swingingly to folded position, a sleeve movable to inclose the overlapped leg portions and lock said parts in alined position, the lower end portion of said leg removably entering the socket member, and a sleeve 55 mounted on the board for holding the supporting leg in folded position.

In testimony whereof I affix my signature.
GEORGE HENRY WHEARY.
